UNITED STATES PATENT OFFICE.

EDWARD JAMES MORIN, OF SIOUX CITY, IOWA.

RATCHET-WRENCH.

SPECIFICATION forming part of Letters Patent No. 781,291, dated January 31, 1905.

Application filed November 9, 1904. Serial No. 231,986.

To all whom it may concern:

Be it known that I, EDWARD JAMES MORIN, a citizen of the United States, and a resident of Sioux City, in the county of Woodbury and State of Iowa, have invented certain new and useful Improvements in Ratchet-Wrenches, of which the following is a specification.

The aim of my invention is to provide a wrench comprising a quick-adjusting traveling head and an adjustable stop-head, between which heads may be adjusted a nut-bar or other device to be promptly engaged; and my invention comprises certain other combinations more fully described hereinafter.

In the accompanying drawings I have shown in Figure 1 an elevation of a wrench embodying my invention. Fig. 2 shows a sectional view of the traveling head. Fig. 3 shows a broken portion of the wrench-stem, 20 showing a rack, while Fig. 4 shows an end view of the traveling head.

As has been stated, the aim of my invention is to provide a wrench arranged so that the same may be quickly adjusted by means of a traveling head provided with a pawl engaging a rack forming part of the wrench-stem, while a fine adjustment is provided by means of the stop-head being revolvably secured to the threaded end of the wrench-stem, so that 30 each revolution of the stop-head brings said stop-head the distance of the thread toward or away from the quick-adjusting traveling head, so that a quick coarse adjustment of the wrench may be instantly secured by means of the traveling head, while the final is secured through the revolvably-supported stop-head.

In the accompanying drawings I have shown a wrench-stem A, which is approximately L-shaped in the cross-section, as is 40 shown in Fig. 2, being provided with a projecting rack B, the flange a acting as a stop for the handle H and the stem b securing the handle, while the opposite end is threaded, as is shown at Fig. 2, to revolvably receive the 45 threaded stop-head C. Traveling upon this

stem A is the sliding quick-adjusting head D, provided with an approximately L-shaped opening, as is shown in Fig. 4, and being further provided with a recess v, as shown in Fig. 1, this recess v entering the socket x. This 50 recess is upon one side of the traveling head E and is provided with a pin 3, upon which is held the stem 4 of the pawl 5, the stem 4 being adapted to engage the rack B, a spring 6 being secured below the pawl-head 5 to normally force the stem 4 into engagement with the rack. It will be noticed that the stem 4 snugly works within the slot of the head D, and this stem 4 locks the sliding jaw. The recess v is sufficiently large to permit an operator depressing the pawl 5 with his thumb or fingers in operating this slotting-head. The head C is threaded, while the end of the stem A is flanged, as shown at 7 in Fig. 1, so that the head C cannot become detached from the 65 wrench-stem. By this means both heads may be adjusted, as set forth.

These wrenches are made of various sizes and of any suitable material.

Having thus described my invention, what 70 I claim as new, and desire to secure by United States Letters Patent, is—

A wrench comprising a stem, having a rack, one end of said stem being threaded, a handle upon the opposite end of said stem, a wrench-head revolvably working upon said threaded end, a wrench-head, slidably working upon said wrench-stem, said slidably head being provided with a slot and recess, a pawl, pivotally working within said slot and recess, and a 75 spring to normally force said pawl in an engagement with said rack, all arranged as set forth.

In testimony whereof I affix my signature in presence of two witnesses.

EDWARD JAMES MORIN.
